EDWARD MERCIER, OF SPRINGFIELD, MASSACHUSETTS, ASSIGNOR TO
HIMSELF AND HENRY W. BAILEY, OF SAME PLACE.

Letters Patent No. 77,510, dated May 5, 1868

IMPROVED RAILROAD-SWITCH.

The Schedule referred to in these Letters Patent and making part of the same.

TO ALL WHOM IT MAY CONCERN:

Be it known that I, EDWARD MERCIER, of Springfield, in the county of Hampden, and State of Massachusetts, have made and invented certain new and useful Improvements in Safety-Switches for Railroads; and I do hereby declare that the following is a full, clear, and exact description of the construction and operation of the same, reference being had to the annexed drawings, making a part of this specification, in which—

Figure 1 is a top elevation of switch and track, and

Figure 2 a perspective view of the safety-piece.

My invention relates to a safety-switch for railroads, more particularly for roads whereon the cars are propelled by steam, and is not applicable in case of more than one side or switch-track.

In all former safety-switches, so far as my knowledge extends, use is made either of "pointed rails," so called, as in Patent No. 29,820, a device which I deem both unsafe and unreliable, or broad exterior inclines and interior guides are connected with and form a part of the moving-switch rails, rendering the whole cumbersome, and difficult to manage or repair; and when this latter arrangement is used, if the switch be misplaced, the wheels, on one side at least, of a passing train, move on the flanges thereof, thus gaining of or advancing faster than the opposite wheels, and this "gain" always happens, from the nature of the case, to be on the wrong side, thereby tending to aggravate rather than mitigate the shock or jar incident to the misplacement of a switch.

My invention is designed to obviate these defects, and to provide a switch at once safe, cheap, manageable, and easy of repair, avoiding the use of "pointed rails," and which, if misplaced, will mitigate the shock or jar incident thereto.

In carrying out my invention, I make use of no unusual apparatus, except the safety-pieces *a a'* and plates *e e'*; in all other respects, I accomplish my object by the use and peculiar arrangement of common rails and switch-machinery, and my peculiar arrangement is as follows: I place the ends of the rails *d d'*, composing the side or switch-track, at a distance of from one and a half to two and one-fourth inches, laterally, from the ends of the rails *c c'*, forming the main track; in other words, I place the ends of the rails composing the main and side tracks as nearly together as possible, and still give free and unobstructed passage to the flanges of wheels moving between them in either direction. I secure the rails *c c' d d'*, thus arranged, on the tie *g*, by means of common spikes.

Next, I place one end of either switch-rail, *b b'*, in the chairs *h h'*, bending such rails, divergently, somewhere near their middles, till the ends thereof opposite the chairs *h h'* are as much further apart than are the exterior rails *c c'* as is equal to the distance between the main and side-track rails *c c'*.

To the inside of the switch-rails *b b'*, thus bent, I bolt firmly the safety-pieces *a a'*, and these safety-pieces I cast, roll, or forge of steel or iron, but I prefer the former material. In shape, I make the safety-pieces *a a'* substantially as seen in fig. 1, consisting of an incline, and a part operating as a "splice-rail," or forming a continuation, in a straight line, of the bent-switch rail, to the inside of which it is attached; but the relative position of the incline and splice-rail must be inverted or varied, of course, to fit the opposite rails of the switch. The rails *b b'*, thus arranged, are held by the switch-bar *B*, and operated by any ordinary switch-machinery.

And further, I provide long stationary guides, *f f'*, which I make of common rail, and arrange inside the switch-rails and safety-pieces, and relatively to the main and side-tracks, substantially as shown in fig. 2, taking care that the guides *f f'* be somewhat longer at each end, and about three-fourths of an inch higher throughout their whole length, than are the switch-rails *b b'*.

By the side of the guides *f f'*, I spike firmly the iron plates *e e'*, which I roll or forge flat, with bevelled ends, and make of about the same height as the rails *d c'*, less the height of the flanges of passing wheels; in other words, I construct and arrange the plates *e e'* in such a manner that the wheels of passing trains will go from the rails *d c'*, where they move on the "tread," to the plates *e e'*, where they move on the "flange," with-

out material rise or fall. The width of the plates $e\ e'$ I make such as to fill the spaces between the guards $f\ f'$ and the tails $d\ d'$ respectively, and I taper the outside edges of the plates $e\ e'$, so that the insides of the safety-pieces $a\ a'$ may come in continuous contact therewith, substantially as shown in fig. 2.

The office of the plates $e\ e'$ is threefold: first, they act as stops or stays to the side motion of the switch; second, they strengthen and support the projecting parts or splice-rail of the safety-pieces $a\ a'$; and, third, they catch and support, in case of a misplaced switch, all wheels of passing trains, until the "treads" of such wheels "bite" on the safety-pieces a or a' , if perchance they do not "bite" thereon from the beginning, which it is intended they shall do.

The safety-pieces $a\ a'$ I arrange, as above-stated, inside the switch-rails $b\ b'$, and it is by this arrangement that I mitigate the shock or jar incident to the misplacement of a switch, for, as will be seen, all wheels of trains passing over the inclines of the safety-pieces move on the flange, and therefore "gain" of the wheels opposite, if moving on the "tread;" but those wheels moving on the flange are, practically, on the outer rail of a curve, the greater length of which very nearly compensates for the "gain" thus made, and prevents the violent lurch or sudden side-motion always experienced if the incline be outside of the switch-rail, as in this latter case the "gain" is on the wrong side or inner rail of a curve, whereby the shock or jar is aggravated.

In fig. 2, the switch is arranged for trains approaching on the side-track $d\ d'$, but should a train approach on the main track $c\ c'$, the wheels on rail c will pass up the incline of safety-piece a , while the wheels opposite move naturally along the splice-rail of safety-piece a' , on which they catch after leaving the rail c' ; but if the wheels, after leaving the rail c' , do not catch on safety-piece a' at first, they will be supported by plate e' until they do so catch or "bite" on such safety-piece; and if the switch be changed or arranged for trains approaching on the main track $c\ c'$, the operation of the switch will be as above described, only on the opposite side.

Having thus described the construction and operation of my invention, what I claim as new, and for which I desire to secure Letters Patent, is—

1. The combination of the fixed guides $f\ f'$ with the sliding safety-pieces or inclines $a\ a'$, substantially in the manner described, and for the purpose specified.
2. I claim the supporting-plates $e\ e'$, arranged and combined with the fixed guides $f\ f'$ and sliding inclines or safety-pieces $a\ a'$, substantially as described, and for the purpose specified.

EDWARD MERCIER.
